CASHIER'S PROTECTOR

Ludwig R. Städltler, New York, N. Y., assignor of
one-half to Leonard Quent, Brooklyn, N. Y.

Application December 21, 1935, Serial No. 55,504

1 Claim. (Cl. 20—1.01)

This invention relates to devices for protecting bank officials, paymasters and like persons from danger by thugs, robbers and assassins.

An object of the invention is to provide an effective defense from depredators, alike avoiding loss of money and life.

Another purpose is to produce such danger deterring means in forms which may be applied to existing structures at a moderate expense.

10 These and like valuable objects are attained by the novel construction and arrangement of parts hereinafter described and shown in the annexed drawing, forming a material part of this disclosure, and in which:

15 Figure 1 is a perspective view showing the general ensemble of a bank structure embodying the improvements.

Figure 2 is a perspective view of the safety window closure elements.

20 Stated in general terms the device consists of a narrow enclosed vestibule into which one or more customers enter through a revolving door, opposite to which is a cashier's window where the financial transactions take place.

25 Should the cashier become alarmed it is possible for him to close the window with a bullet proof shutter.

Referring in greater detail to the drawing, the numeral 15 designates a platform or floor from 30 which rise the walls 16 of a preferably narrow compartment 17, the upper portion of its walls being formed of spaced overlapping impregnable plates 18 and covered by a roof 19.

This compartment is directly in front of the 35 cashier's room, and the entrance is controlled by a revolving door 20, its wings filling the entire passage.

The opposite end of the compartment is separated from the cashier's room by an impregnable 40 wall constituting a partition 25, having on its lower portion a shelf 26 extending into the com-

partment 17, and in which is revolvably mounted a circular money transfer tray 27.

Above the tray in the partition 25 is a framed window 35 separating the cashier's room from the customers' room, the window being provided with a 5 sliding shutter 36 to be actuated, if desired, by the cashier, and at the front of the window is a metal screen 37 hinged on pins 38.

This screen is formed to present a convexly curved surface directed towards the cashier's 10 room and is controlled by a roll 39 carried by a lever 40 pivoted to the frame 35 and provided with an operating handle 41 accessible to the cashier, the function of the curved screen being 15 to deflect bullets from the cashier's room to the customers' compartment from whence they may come. The metallic slide or shutter 36 is also provided for a similar purpose.

From the foregoing, it will be seen that a cashier is safely protected from danger in case of 20 robbery and that the robber may be held until the authorities have been called to arrest such parties as are within the customers' compartment, escape being rendered substantially impossible.

25 Having thus described the invention what is claimed as new and sought to secure by Letters Patent, is:

In a protective device for a cashier's room having a customers' compartment adjacent and an 30 impregnable wall therebetween provided with a window having a frame, a convexly curved impregnable shutter pivoted at its lower edge to said frame, a lever pivoted to said frame near its upper part, a roll carried by said lever to contact said 35 shutter whereby it may be swung upwardly to close the window space, a handle on said lever, all of said elements extending into the cashier's room and a metal slide movable to close the window. 40
